UNITED STATES PATENT OFFICE.

JOSEPH CHARLES WILLIAM LLOYD, OF ALPERTON, ENGLAND.

MEANS FOR CONTROLLING ADMISSION AND EXHAUST IN DOUBLE-ACTING EXPLOSION-ENGINES.

1,388,352.

Specification of Letters Patent. Patented Aug. 23, 1921.

Application filed September 20, 1918. Serial No. 255,004.

To all whom it may concern:

Be it known that I, JOSEPH CHARLES WILLIAM LLOYD, a subject of the King of Great Britain and Ireland, residing at Alperton, in the county of Middlesex, England, have invented certain new and useful Improvements in Means for Controlling Admission and Exhaust in Double-Acting Explosion-Engines, of which the following is a specification.

This invention relates to double acting explosion engines working on the four-stroke cycle and in which the admission and exhaust is controlled by concentric slide valve and sleeve-operated by time eccentric device of the kind giving double acting, silent and positive movement to the valves, the object being to provide an improved apparatus of this kind.

According to this invention the concentric slide valve and sleeves are arranged within auxiliary cylinders, independent of the main cylinders but communicating therewith. Each auxiliary cylinder communicates with two of the main cylinders, thus controlling the admission and exhaust of two main cylinders at the same time.

Each of the auxiliary cylinder valve and sleeve functions for the top of one main cylinder and the bottom of the adjacent main cylinder.

The cranks of the main cylinders are arranged so that the angle between the cranks of two cylinders is 180° while the sleeve and slide valve is driven at half the speed of the crank shaft and may be operated by two rods pivotally connected to two eccentrics or cranks on one shaft about 90° to each other.

The admission preferably communicates midway in the auxiliary cylinder by annular openings extending around the said auxiliary cylinder, through lateral openings in the sleeve valve and around the circumferential throat arranged midway of the length of the slide valve.

Or as an alternative method of operation, the admission may communicate at the end of the auxiliary cylinder by an axial opening in the slide valve and annular openings around the auxiliary cylinder.

The valve comprises a sleeve open at both ends and having lateral openings which will slide within the auxiliary cylinder and be brought into position with its lateral open-

ings, opposite the lateral openings between the main and auxiliary cylinders, and the slide valve which will reciprocate within the sleeve, and the said valve adapted either to cover or uncover the lateral openings in the sleeve when the same is opposite the openings communicating with the main cylinder to place this cylinder in communication with admission and exhaust alternately.

The exhaust pipe may communicate from midway of the auxiliary cylinder to the main cylinder through the circumferential throat arranged midway of the length of the slide valve.

The exhaust pipe preferably communicates from one end of the auxiliary cylinder to the main cylinder through an axial opening in the slide valve.

In the accompanying drawing:

Figure 1 is a sectional elevation of the two main cylinders and one auxiliary cylinder.

Fig. 2 is a cross-sectional elevation of the two auxiliary cylinders and one main cylinder.

Fig. 3 is a development of the two main and two auxiliary cylinders, showing the movement of the valves.

Fig. 4 is a plan of the cylinders.

The motor consists of two main cylinders **a** and **b** in Figs. 1, 2, 3 and 4, in which move pistons **a'** and **b'** acting on the crank shaft **c** in Figs. 1 and 2. Parallel with the main cylinders **a** and **b** are mounted two auxiliary cylinders **d** and **e** in Figs. 1, 2 and 3 of smaller diameter than the main cylinders **a** and **b** and communicating with the latter by lateral passages **a²**, **a³**, **b²** and **b³** in Figs. 1, 2 and 3, in which auxiliary cylinder **d** opens by passage **b²** to top of main cylinder **b** and by passage **a²** to bottom main cylinder **a**, also auxiliary cylinder **c** opens by passage **a³** to top main cylinder **a** and by passage **b³** to bottom main cylinder **b**.

In the auxiliary cylinder **d** and **e** are arranged two slide valves—a sleeve **f** in Figs. 1, 2 and 3, slide **g** in Figs. 1, 2 and 3, mounted concentrically one in the other—the sleeve **f** being provided near the middle and ends with a ring or orifices **h**, **h'** and **h²** in Figs. 1, 2 and 3, while the slide **g** is provided also at the middle with a throat or reduced portion **g'**. The sleeve **f** and the slide **g** are connected by their respective rods **k** and **l** in Figs. 1, 2 and 3, to eccentric

trics secured 90° apart on a shaft m in Figs. 1, 2 and 3 to which the rotatory motion of the driving shaft c is transmitted at half speed by wheels n and o in Figs. 1 and 2. 5 The ends of the auxiliary cylinders d and e communicate with the exhaust pipe p in Figs. 1 and 2, and the said auxiliary cylinders d and e are provided between the annular passages d' and d^2 in Figs. 1, 2 10 and 3 with another annular passage d^3 in Figs. 1, 2 and 3 into which opens the admission pipe q in Fig. 2. The sleeve f and the slide g both between themselves and in combination with the cavities d' , d^2 and d^3 15 play the part of the slide valves.

The motor according to this invention works in the same manner as a four-stroke motor as follows:—

Assuming the parts to be in position for 20 the commencement of admission, at the bottom of piston b' in Figs. 1 and 2, that is to say, at the moment when the piston b' after the expulsion of the consumed gases is at the dead point of its stroke preceding 25 the aspiration period in that portion of the parts, the orifices h^2 of sleeve f coincide exactly with the annular cavity e^2 but are closed by slide g so that there is no communication between any of the openings in 30 the motor and the outside.

The half-speed shaft m turning in the direction of the arrow, as soon as the sleeve f begins its up stroke, the slide g which is then on the down stroke, uncovers the orifices h^2 which then come into position opposite the annular cavity e^2 and passage b^3 . 35

It follows that in proportion, as the piston b' moves and produces a vacuum in its rear, the sleeve f and slide g increase progressively the sectional area for the passage 40 of the explosive mixture, which therefore enters the cylinder b through the throat of the slide g as well as through such portions of the orifices h^2 as are in communication 45 with the cavities e^2 and e^3 as shown in Figs. 1, 2 and 3.

When the piston b' reaches the end of its admission stroke the half-speed shaft has made $\frac{1}{4}$ turn, bringing the sleeve f and slide g into a position for shutting off the admission 50 completely, as shown at a^2 in auxiliary cylinder d . The piston continuing its stroke and moving downward in order to compress the admitted mixture, the sleeve f and 55 slide g move without uncovering any of the orifices.

The same occurs during the period following the displacement of the piston b' , that is to say, the period corresponding to 60 the active phase or working stroke of the motor and following the explosion.

When the piston b' has reached the end of its working stroke and is about to expel the burned gases, the sleeve f and slide g

move simultaneously upward in order to 65 uncover the orifices h^2 and g^2 and place the cylinder b in communication with the exhaust pipe p shown at d' of annular cylinder d .

At the end of the expulsion or scavenging 70 stroke of the piston b' , the sleeve f and slide g close the exhaust passages and reopen the admission passages, thus renewing and containing the cycle of the motor.

The timing of the sleeves f and f , and 75 slides g and g are shown suction at the bottom and firing at the top of auxiliary cylinder c , also compressing at the bottom and exhaust at the top of the auxiliary cylinder d . 80

Having now described my invention, what I claim as new and desire to secure by Letters Patent is:—

1. An explosion motor of the class referred to and having double-acting reciprocating concentric slide and sleeve valves arranged within auxiliary cylinders independent of the main cylinders but communicating therewith and operating for the two main cylinders simultaneously; in which each auxiliary cylinder communicates with the admission pipe at midway of the length of said auxiliary cylinder, with the exhaust pipe at the top of the auxiliary cylinder, and with the top end of one main cylinder and the bottom end of another main cylinder by lateral openings. 90 95

2. Apparatus of the kind specified in claim 1, in which a sleeve open at both ends and provided with lateral openings reciprocates within the auxiliary cylinder, and a hollow cylindrical slide valve with a narrow throat about midway of its length reciprocates within the sleeve, for the purpose set forth. 100 105

3. Apparatus of the kind specified in claim 2, in which the sleeve and the slide valve are operated by two rods connected to eccentrics or crank pins on the shaft at about 90° to each other, the said shaft being driven at half the speed of the main crank shaft. 110

4. An explosion motor of the kind specified in claim 1, comprising in combination with an auxiliary shaft at right angles to the main crank shaft driven at half the speed thereof, and cranks or eccentrics on the auxiliary shaft for driving the two sleeves and the two slide valves, two main cylinders, a main crank shaft with two cranks at 180° , connecting rods, pistons reciprocating within the cylinders, and two auxiliary cylinders within each of which reciprocate a sleeve and a concentric slide valve. 115 120 125

In testimony whereof I have signed my name to this specification.

JOSEPH CHARLES WILLIAM LLOYD.
